Specification for Design.

Patented Sept. 8, 1914.

Application filed June 10, 1914. Serial No. 844,353. Term of patent 7 years.

To all whom it may concern:

Be it known that I, GRANT F. DISCHER, a citizen of the United States, residing at Milwaukee, in the county of Milwaukee and State of Wisconsin, have invented a new, original, and ornamental Design for Tire-Supporting Brackets for Automobiles, of which the following is a specification, reference being had to the accompanying drawing, forming a part thereof.

Figure 1 of the drawing is a side elevation, Fig. 2 a top plan view, and Fig. 3 an

inverted plan view of a tire supporting bracket for automobiles, showing my new design.

I claim:

The ornamental design for a tire supporting bracket for automobiles, substantially as shown.

GRANT F. DISCHER.
